UNITED STATES PATENT OFFICE.

GEORGE HENRY WHEARY, OF RACINE, WISCONSIN.

CLOSET-FIXTURE.

1,235,267.

Specification of Letters Patent. Patented July 31, 1917.

Application filed March 20, 1915. Serial No. 15,850.

To all whom it may concern:

Be it known that I, GEORGE HENRY WHEARY, a citizen of the United States, and resident of Racine, in the county of Racine and State of Wisconsin, have invented new and useful Improvements in Closet-Fixtures, of which the following is a description, reference being had to the accompanying drawings, which are a part of this specification.

This invention relates to improvements in closet fixtures for supporting wearing apparel.

It is one of the objects of the present invention to provide a closet fixture upon which garment hangers may be mounted in such a manner as to prevent their surreptitious removal by unscrupulous persons.

A further object of the invention is to provide a closet fixture provided with slideable garment hangers which may be easily moved to drape garments thereon or remove them therefrom without permitting the hangers being surreptitiously removed from the fixture.

A further object of the invention is to provide a closet fixture in the form of a single track for holding garment hangers locked thereon and having means whereby the hangers may be easily removed by unlocking a portion of the fixture.

A further object of the invention is to provide a closet fixture having an extensible track end which may be swung to aligned position with the fixed portion of the track to permit the hangers mounted thereon being separated to easily remove or replace garments thereon.

A further object of the invention is to provide a closet fixture in which the means for locking the removable portions of the track also serves as a guard for preventing the surreptitious removal of the fixture from its support.

A further object of the invention is to provide a closet fixture which is of simple construction, is strong and durable and is well adapted for the purpose described.

With the above and other objects in view the invention consists of the improved closet fixture and its parts and combinations as set forth in the claims, and all equivalents thereof.

In the accompanying drawing in which the same reference characters indicate the same parts in all of the views:

Figure 1 is a top view of the improved closet fixture shown mounted on a support, the extensible end member being indicated in closed position by dotted lines, the view 60 also showing portions of garment hangers mounted thereon;

Fig. 2 is a sectional view thereof taken on line 2-2 of Fig. 1;

Fig. 3 is an enlarged sectional detail 65 view taken on line 3-3 of Fig. 2;

Fig. 4 is a top view of a modified form of fixture;

Fig. 5 is an enlarged sectional detail 70 view thereof taken on line 5-5 of Fig. 4; and

Fig. 6 is a transverse sectional view taken on line 6-6 of Fig. 5.

Referring to the drawing the numeral 8 indicates a support and 9 the improved 75 closet fixture mounted thereon. The fixture comprises the rear securing plate 10 having a forwardly projecting rod or track 11 upon which eyed garment hangers 12 are slidably mounted. The rod or track is 80 round in cross section and has a threaded engagement 13 with the rear securing plate 10 as indicated in Fig. 3 and at its forward end is provided with a hinged extension 14 which can be swung horizontally from an 85 outer position aligned with the fixed portion of the track to an inner or closed position extending at right angles to the said fixed track.

The extension track is also round in cross 90 section and the garment hangers are provided with central upstanding rods 15 having eyed portions 15' formed on their upper ends through which the track member extends. The outer end of the extensible rod 95 is provided with a stop knob or enlargement 16 which is of larger diameter than the eyed portion 15' of the hangers so that the said hangers cannot be removed from the track by pulling them off the outer ends of the 100 rods.

The inner end portion of the fixed track adjacent the securing plate 10 is recessed transversely, vertically on one side to form a slotted or flat portion 17 into which extends the locking member 18 carried by the locking bar 19. The locking member 18 has a lower bifurcated portion which straddles the track with the portion 18' entering the transversely extending recess and engaging 110 the slotted or flat portion thereof and thus prevents the track 11 from being surrepti-

tiously unscrewed from the securing plate and the hangers removed from the fixture.

The locking bar is hinged or pivoted at one end to the securing plate 10 by a pivot pin 20 and at its opposite end is provided with a depending tongue 21 which enters the lock 22 mounted on the securing plate 10 and locks the bar 19 in track engaging position. The lock 22 is controlled by a key 23.

The securing plate 10 is connected to a support by screws 24, a number of which are positioned in the rear of the locking bar 19 and cannot be unscrewed unless the locking bar has been swung to open position.

In the modified form shown in Figs. 4, 5 and 6 the fixed track 11' is in two parts and the said parts are hinged together close to the threaded end as indicated by the numeral 25 to permit said bar to be folded close to its support when desired. The joint provides for the outer part swinging horizontally to open or folded position and is locked in open position by means of a slideable and revoluble locking sleeve 26 mounted on the fixed track. This locking sleeve when in locking position extends over the hinge and is of sufficient length to prevent movement of the outer track part. The sleeve is also provided with a bayonet slot 27 which is entered by a locking pin 28 to lock the sleeve in joint locking position.

This form of fixture is also provided with an outer extensible hinged track 14 similar to the extension track of the first mentioned form.

The fixed track is connected to the securing plate in the same manner as the first mentioned form and the same reference numerals will apply.

In use the extensible track is swung into alignment with the fixed track to provide sufficient space to separate the hangers and permit the removal of the garments therefrom. The extensible track also serves when in closed or folded position to prevent the hangers working outwardly.

While the fixture has been described as a closet fixture and more particularly adapted for use in hotels, it is to be understood the fixture is also useful in private houses and other places than closets.

From the foregoing description it will be seen that the closet fixture is of simple construction and is well adapted for the purpose described.

What I claim as my invention is:

1. A closet fixture, comprising a securing member having means for connecting it to a support, a garment hanger track member removably connected to the securing member and projecting horizontally outwardly therefrom and having a stop means on its outer end, locking means for preventing the

surreptitious removal of the track member from the securing member, and a garment hanger having a medial eyed portion through which the track member extends, the opening of said eyed portion being of such diameter as to prevent the hanger from passing over the stop means, said locking means also locking the hanger on the track member against surreptitious removal.

2. A closet fixture, comprising a securing member having means for connecting it to a support, a garment hanger track member removably connected to the securing member and projecting horizontally outwardly therefrom and having a stop means on its outer end, locking means for preventing the surreptitious removal of the track member from the securing member and the securing member from its support, and a garment hanger having a medial eyed portion through which the track member extends, the opening of said eyed portion being of such diameter as to prevent the hanger from passing over the stop means, said locking means also locking the hanger on the track member against surreptitious removal.

3. A closet fixture, comprising a securing member having means for connecting it to a support, a garment hanger track member revolvably connected to the securing member and projecting horizontally outwardly therefrom and having a stop means on its outer end, a locking means for locking the track member against rotation and for preventing the surreptitious removal of the securing member from its support, and garment hangers having medial eyed portions through which the track member extends, the openings of said eyed portions being of such diameter as to prevent the hangers from passing over the stop means, said locking means also locking the hanger on the track member against surreptitious removal.

4. A closet fixture, comprising a securing member having means for connecting it to a support, a horizontally extending garment hanger track member having a threaded engagement at its inner end with the securing member and a stop means on its outer end, said track member also having a flattened portion adjacent its connection with the securing member, a locking member having a slotted portion engaging the flattened portion of the track member to prevent its rotation, and garment hangers having medial eyed portions through which the track member extends, the openings of said eyed portions being of such diameter as to prevent the hangers from passing over the stop means, said locking member locking the track member to the securing member and the hangers on the track member against surreptitious removal.

5. A closet fixture, comprising a securing

member having means for connecting it to a support, a horizontally extending garment hanger track member having a threaded engagement at its inner end with the securing member and provided with a flattened side portion adjacent its connection with the said securing member, a locking bar pivoted at one end to the securing member and having a locking engagement at its other end with 5 said securing member, a medial portion of said bar having a slotted portion which engages the flattened portion of the track member to prevent said track member from being unthreaded from the securing plate, an extension track member hinged to the outer end of the track member and provided with stop means at its outer end, and garment hangers having medial eyed portions through which the track members extend, the openings of 10 said eyed portions being of such diameter as to prevent the hangers from passing over the stop means, said locking bar also locking the hangers on the track member against surreptitious removal.

20 6. A closet fixture, comprising a securing member having means for connecting it to a support, a horizontally extending two-part-hinged-together garment hanger track member having a threaded engagement at its inner end with the securing member and projecting outwardly therefrom, a sleeve slidably mounted on the track member and movable to a position surrounding the hinged connection of the track parts to lock said parts in alined position with respect to each other, means for locking the sleeve in its hinge locking position, a locking means for locking the track member 25 against rotation, an extension track hinged to the outer end of the first mentioned track member and provided with stop means on its outer end, and garment hangers having medial eyed portions through which the track member extends, the openings of said eyed portions being of such diameter as to prevent the hangers from passing over the stop means, said locking means also locking the garment hangers on the track member 30 against surreptitious removal.

25 7. A closet fixture, comprising a securing member having means for connecting it to a support, a horizontally extending two-part-hinged-together garment hanger track member having a threaded engagement at its inner end with the securing member and projecting outwardly therefrom, a sleeve slidably mounted on the track member and movable to a position surrounding the hinged connection of the track parts to lock said parts in alined position with respect to each other, means for locking the sleeve in its hinge locking position, a locking means for locking the track member 35 against rotation, an extension track hinged to the outer end of the first mentioned track member and provided with stop means on its outer end, and garment hangers having medial eyed portions through which the track member extends, the openings of said eyed portions being of such diameter as to prevent the hangers from passing over the stop means, said locking means also locking the garment hangers on the track member 40 against surreptitious removal.

having medial eyed portions through which the track member extends, the openings of said eyed portions being of such diameter as to prevent the hangers from passing over the stop means, said locking means also locking the garment hangers on the track member 45 against surreptitious removal.

7. A closet fixture, comprising a securing member having means for connecting it to a support, a horizontally extending two-part-hinged-together garment hanger track member having a threaded engagement at its inner end with the securing member and projecting outwardly therefrom, a sleeve slidably mounted on the track member and movable to a position surrounding the hinged connection of the track parts to lock said parts in alined position with respect to each other, means for locking the sleeve in its hinge locking position, a locking means for locking the track member 50 against rotation, an extension track hinged to the outer end of the first mentioned track member and provided with stop means on its outer end, and garment hangers having medial eyed portions through which the track member extends, the openings of said eyed portions being of such diameter as to prevent the hangers from passing over the stop means, said locking means also locking the garment hangers on the track member 55 against surreptitious removal.

In testimony whereof, I affix my signature, in presence of two witnesses.

GEORGE HENRY WHEARY.
